UNITED STATES PATENT OFFICE.

FRANK W. KNEBUSCH, OF WOODSTOCK, ILLINOIS.

BOWLING-GAMES APPARATUS.

Application filed September 13, 1926. Serial No. 135,225.

This invention relates to games and more particularly to game apparatus of the bowling alley type, being designed as an improvement of the apparatus shown in Patent No. 5 1,545,778, dated July 14, 1925.

Having in view such improvement, one of the primary objects of the invention is to provide a game board of the general nature of a bowling alley, there being provided a 10 unique arrangement of stalls or pockets to receive the balls thereby instilling an element of skill into the rolling of the balls into the pockets.

Another object is to provide a game board 15 of this type equipped with a chute board having a plurality of gullies or grooves terminating in stalls or pockets so that when a ball enters one of these grooves it will roll to a stall and close a contact indicating 20 on a suitable register the stall which it has entered.

With the foregoing and other objects in view the invention consists in the novel construction and arrangement hereinafter 25 described and claimed, the description being supplemented by the accompanying drawings in which,

Figure 1 represents a longitudinal section of the game apparatus constructed in accordance with this invention,

Figure 2 is a horizontal section taken on the line 2—2 of Figure 1,

Figure 3 is a top plan view of the apparatus,

Figure 4 is an enlarged detailed vertical section of a fragment of the apparatus,

Figure 5 is a transverse section taken on the line 5—5 of Figure 4, and

Figure 6 is a similar view taken on the 40 line 6—6 of Figure 4.

In the embodiment of the invention illustrated, the game apparatus is in the form of a bowling table which may be of any desired type and proportions, being preferably 45 constructed in sections and made approximately 30 feet in length and 32 inches wide. The alley over which the balls roll shown at 2, has an incline of about 3 inches from the foot to the head of the alley, it being

understood, of course, that the ball is rolled to the head of the alley.

The bowling table 1 is in the form of an elongated casing, the top of which forms the alley 2 which is equipped at its edges with gutters 3 and 4 and has up-standing sides or ledges 5 to prevent the balls straggling over the sides of the table. These ledges 5 merge at the front of the apparatus in side plates 6, which constitute part of a cabinet presently to be described. The bottom 7 of the casing is provided at one side with a ball-return race 8 which delivers the balls to a rack 9 at the rear or foot of the table. A ball guide 10 extends obliquely across the bottom 7 at the front end or head 60 of the apparatus to direct the balls which drop into the pit to the return passage.

At the head of the casing or alley, a cabinet 11 is provided containing electric lights 12 and provided with transparent panels 13 bearing legends to be used in keeping the score of the game. These legends preferably represent "seven pins", "nine pins", "strike", "spare" and "eight pins", arranged as shown in Figure 5. It is to be understood that one of the lights 12 is arranged behind each panel 13, provision for completing the circuit of the electric lights being made and will be hereinafter more fully described. The front end or head of the alley 2 is provided with an opening 14 below which is arranged an outwardly extending chute board 15 which is divided by vertical partitions 15^a secured rigidly thereto; into a plurality of chutes 16, five of which are here shown and 85 which extend longitudinally from the top to the bottom of the chute board and are designed to receive the balls entering through the opening 14 and conduct them to stalls or pockets 17 formed at the bottom of the 90 chutes. The only balls which assist illumination of the lights 12 are those which enter through the opening 14 and pass through the chutes 16 to the stalls at the bottom thereof. These stalls or pockets 17 correspond in 95 number to the electric lights 12, and normally open switches 18, provided for said lights, are located in said pockets. At the

lower end of the chute board 15 is arranged a transversely extending barrier 19 which forms the lower wall of the stalls or pockets 17 but is free from the partitions 15^a and 5 adapted to swing outwardly and is equipped with spring hinges to hold it normally in closed position. The switches 18 are carried by the barrier 19 as shown clearly in Figure 4 so that when a ball rolls down one 10 of the chutes 16, it will close the switch 18 and light the lamp 12 in the rear of the panel above it, thereby registering on the indicator board on which these panels are mounted, the pocket which has been entered 15 by the ball after passing through the opening 14. A swinging bumper or baffle 21 is arranged transversely of the alley at the head of the table above the chutes 16 so that the ball will strike this cushioning 20 bumper and drop into the opening 14 onto the chute board and roll down through one of the chutes to the stall at the bottom thereof.

The gutters 3 and 4 at the sides of the 25 alley also discharge into the pit 20 and are provided near the head of the alley with bumpers or swinging cushions 3^a and 4^a to retard the speed of the ball in its passage to the pit.

30 For clearing the stalls or pockets 17 of balls, the barrier 19 is provided with means for swinging it forwardly to permit the balls to roll into the pit 20 and be directed by the guide strip 10 to the return passage 8. The means here shown for swinging the barrier consists of a pull rod 22 mounted in suitable guides 23 along one side of the casing or table, and is made in two sections, with a knuckle joint 24 connecting them.

35 The front section 25 of this pull rod is connected with the lever 26 fulcrumed at 27 and connected at 28 with the barrier 19 so that a pull exerted on the rod 22 will swing the lever on its fulcrum and open the barrier 19 in the dotted line position shown in Fig. 4. This opening of the barrier permits the 40 ball which has entered a stall to roll down into the pit 20 and drop into the runway 8 and be guided thereby back to the rack at the foot of the alley.

In the use of this apparatus, the game is 45 played very similar to an ordinary game of bowling and any ball which is rolled along the alley 2 and enters one of the gutters 3 or 4 drops into the pit 20 and does not add to the player's score. However, any ball which passes through the opening 14, finds its way into one of the chutes 16 and passes into the stall 17 at the lower end of the chute. These 50 stalls have different counting values as shown by the legends on the panels 13. If a ball passing through the opening 14 enters the third stall, the light 12 for the "strike" legend is illuminated and the other lights are, of course, lighted whenever the ball reaches

their respective pockets, thus indicating the score of the player.

The apparatus is preferably constructed in sections and made portable, being equipped with legs 9, adapted to be readily transported 70 from place to place, and may be installed with very little trouble.

I claim:

1. A game apparatus comprising an alley, a chute board extending downwardly and 75 forwardly at one end of the alley, a series of partitions rigidly secured to said chute board to form a plurality of chutes having separate ball receiving pockets at their lower ends, said pockets having different counting 80 values, a barrier at the lower end of said chutes forming one wall of said pockets, said barrier being free from said partitions and movable to release the balls from said pockets, and ball actuated indicator means for 85 disclosing into which pocket the ball enters.

2. A structure as specified in claim 1; said indicator means comprising switches carried by the barrier and closable by the ball.

3. An apparatus comprising a casing the 90 top of which forms an alley with gutters at either side thereof, a pit located at one end of said casing into which said gutters discharge, a chute board extending downwardly and forwardly from the alley, a series of 95 partitions rigidly secured to said chute board to form a plurality of chutes discharging into the pit, a barrier at the lower end of said chutes but free from said partitions, separate ball receiving pockets at the lower 100 ends of said chutes partially formed by said barrier, said pockets having different counting values, ball actuated indicating means for disclosing into which pockets the balls enter, means for moving said barrier to clear 105 the pockets from the balls which have fallen therein and a ball returning passage connected with said pit to return the balls to the outer end of the casing.

4. A game apparatus comprising a casing 110 whose top forms an alley and which has a pit arranged at one end thereof, a chute connecting said alley with the pit, a ball-return runway leading from said pit, gullies formed on said casing in said chute to receive the 115 balls from said alley, cushioning means located in the path of the balls to break their speed in their passage to the chute, a hinged barrier at the lower end of the chute forming one wall of the said gullies, ball actuated 120 indicating means for disclosing into which gully the ball enters, and lever controlled means for moving said barrier to return the balls.

5. A game apparatus comprising a casing 125 whose top forms an alley having gutters along opposite sides thereof swinging bumpers near the discharge ends of said gutters, a pit at the front of said casing into which said gutters and alley discharge, a forwardly 130

and downwardly inclined chute board extending from said alley into said pit, ball-receiving gullies extending longitudinally of said chute board and terminating at their lower ends in separate pockets, a barrier arranged at the lower end of said chute between it and the pit, and forming one wall of said pockets ball-actuated switches carried by said barrier, indicating means connected with said switches for disclosing into 10 which gulley the ball enters, means for clearing the chute gullies of the balls, and a ball-return runway connected with the pit.

In testimony whereof I have hereunto affixed my signature.

FRANK W. KNIEBUSCH.
